UNITED STATES PATENT OFFICE

149,949

DESIGN FOR AN AIR DISTRIBUTION
OUTLET

Walter W. Kennedy, Rockford, Ill., assignor to
Barber-Colman Company, Rockford, Ill., a cor-
poration of Illinois

Application April 25, 1946, Serial No. 128,960

Term of patent 14 years

(Cl. D62—4)

To all whom it may concern:

Be it known that I, Walter W. Kennedy, a citizen of the United States, residing at Rockford, in the county of Winnebago and State of Illinois, have invented a new, original, and ornamental Design for an Air Distribution Outlet, of which the following is a specification, reference being had to the accompanying drawings, forming a part thereof.

In the drawings:

Figure 1 is a side elevation of an air distribution outlet shown partly in section, embodying my new design, and

Fig. 2 is a bottom plan view of said outlet.

Fig. 3 is a view in perspective of the air distribution outlet disclosed in Figs. 1 and 2.

I claim:

The ornamental design for an air distribution outlet, substantially as shown,

WALTER W. KENNEDY.
